[57] **CLAIM**

The ornamental design for a suture package, as shown and described.

DESCRIPTION

FIG. 1 is a top perspective view of a suture package, showing my new design;
FIG. 2 is a bottom perspective view thereof;
FIG. 3 is a bottom plan view thereof;
FIG. 4 is an end elevational view thereof;
FIG. 5 is an end elevational view thereof, opposite that shown in FIG. 4;
FIG. 6 is a side elevational view thereof;
FIG. 7 is a side elevational view thereof, opposite that shown in FIG. 6;
FIG. 8 is a cross-sectional view thereof, take along the line 8—8 of FIG. 6;
FIG. 9 is a top perspective view of a second embodiment of the suture package;
FIG. 10 is a bottom perspective view thereof;
FIG. 11 is a bottom plan view thereof;

FIG. 12 is an end elevational view thereof;
FIG. 13 is an end elevational view thereof, opposite that shown in FIG. 12;
FIG. 14 is a side elevational view thereof;
FIG. 15 is a side elevational view thereof, opposite that shown in FIG. 14;
FIG. 16 is a cross-sectional view thereof, take along the line 16—16 of FIG. 14;
FIG. 17 is a top perspective view of a third embodiment of the suture package;

FIG. 18 is a bottom perspective view thereof;
FIG. 19 is a bottom plan view thereof;
FIG. 20 is an end elevational view thereof;
FIG. 21 is an end elevational view thereof, opposite that shown in FIG. 20;
FIG. 22 is a side elevational view thereof;
FIG. 23 is a side elevational view thereof, opposite that shown in FIG. 22; and,
FIG. 24 is a cross-sectional view thereof, taken along the line 24—24 of FIG. 23.
